UNITED STATES PATENT OFFICE.

EDWARD B. HESS, OF NEW YORK, N. Y., ASSIGNOR, BY MESNE ASSIGNMENTS, TO
ROYAL TYPEWRITER COMPANY, INC., OF NEW YORK, N. Y., A CORPORATION OF
NEW YORK.

TYPE-WRITING MACHINE.

1,165,171.

Specification of Letters Patent. Patented Dec. 21, 1915.

Application filed April 1, 1911. Serial No. 618,932.

To all whom it may concern:

Be it known that I, EDWARD B. HESS, a citizen of the United States of America, residing in the borough of Manhattan, city, county, and State of New York, have invented a certain new and useful Improvement in Type-Writing Machines, of which the following is a specification.

In Letters Patent of the United States, 10 No. 950,326, issued to me February 22, 1910, I have shown paper or card holders co-operating with the platen and extending up in front of it across the line of print. These 15 holders are arranged on both sides of the printing point and are carried in the ends of standards or paper guiding arms mounted below the platen on the main frame or on the carriage shift rail. They are, therefore, stationary with respect to the transverse traverse of the platen. They are normally permanently attached to the machine but are detachably secured so that they are capable of removal and replacement when 20 specially desired. The primary purpose of 25 that invention is to hold cards or stiff sheets close against the platen at and above the printing line so as to insure good impressions of the types.

The present invention comprises an improvement upon the organization disclosed in said patent and consists in mounting the card holders, or either of them, so that they may be swung on a pivot from in front of the line of print to expose it to unobstructed view. The holders should preferably be permanently attached to their support or standards in such way that they may be swung down from in front of the printing line to expose it to view. Thus the 40 holders may be, and preferably are, hinged so that they may be swung laterally downward out of the way. With reference to the support carrying the holders it should be said that it may assume a variety of forms. 45 As herein shown it is a plate screwed to the shift rail and formed in its upper part with two arms or bifurcations that constitute standards, one on each side of the printing point. Sometimes it is desirable to employ 50 with card holders a printing line scale and so in the present case I have shown one attached to or forming part of the two arms or standards. Its scale edge lies closely adjacent or at the base of a line being printed. 55 When writing upon ordinary sheets and the

card holders are not requisite or desired they may be swung out of the way and so remain until the operator again requires them. The card holders may be in the form of rollers whose axes are transverse to that 60 of the platen, or they may be made of flat metal fashioned into concavo-convex form, the convex faces curved in the direction of the length of the platen, extending across the line of print and cooperating with the 65 surface of the platen. In either case the holders are preferably made to conform in vertical lines more or less closely to the curvature of the platen; and in either case, their curvature serves to direct the edge of 70 cards or paper under them in the lateral movement of the carriage in either direction.

In the accompanying drawings: Figure 1 is a front elevation showing so much of the apparatus as is deemed necessary to illustrate the invention. Figs. 2 and 3 are detail views on an enlarged scale showing the manner in which the hinged roller paper holders may be swung from in front of the printing 75 line: Fig. 4, a front elevation showing a 80 modification consisting in the employment of clamps or holders that may be made of sheet metal: Fig. 5, a transverse section on an enlarged scale showing a card paper holder such as shown in Fig. 4 mounted to be swung 85 forward out of operative position: Fig. 6, a transverse section on line 6, 6, of Fig. 4. Fig. 7, is a plan view of the right hand end of Fig. 4 with the card paper holder swung laterally out of operative position: Fig. 8, 90 a detail view showing a metal plate holder adapted to be entirely removed from its support: Fig. 9, a front elevation showing roller holders, the left hand one of which is capable of removal from its supporting arm. 95 Fig. 10 is a view similar to Fig. 9 showing round roller-like holders not, however, adapted to rotate but capable of being entirely removed from their supporting arms.

The drawings may be taken as an illustration of the application of this invention to the Royal Standard machine.

a indicates the ordinary transversely movable rotatable platen broken away at both ends. All parts of the carriage and the 105 paper feed devices are omitted except that the shift rail *c* and front feed rolls *b* are indicated in Fig. 1.

d is an ordinary type bar guide of common construction to be secured as usual to the 110

segment in which the type bars are pivoted; and *e* an ordinary ribbon vibrator movable up and down and guided on the standard of the type bar guide as is usual.

5 On the shift rail *c* is mounted a light frame *f*, preferably of sheet metal, that extends upwardly in the general manner shown in my patent above mentioned. The upper part of this frame is bifurcated, being formed as 10 two standards, *g*, *h*, that extend upwardly in front of the platen in close proximity thereto. They may serve to assist in directing the paper upwardly to the printing line. As shown, the scale *i* is attached to the rear 15 faces of these arms or standards *g*, *h*, by screw bolts *i'*. The scale lies suitably adjacent the face of the platen and its upper edge is closely adjacent or at the line of print. Opposite the type bar guide, behind 20 which it lies, it has a notch to permit the types to print through the ordinary ribbon upon the paper or card on the platen. The tops of the arms *g*, *h*, terminate at or below the line of print and have permanently 25 hinged to them card holders in the form of rollers *g'*, *h'*. These rollers taper inwardly from their upper ends downwardly in curved lines so that they approximately conform to the curvature of the platen, 30 and, as in my before mentioned patent, are out of contact with the surface of the platen, as seen in Fig. 2. They are attached to their standards by hinge joints *j*, whose axes are parallel with the axis of the 35 platen. They may therefore be swung to the front or toward the operator into the position shown in Fig. 3. When elevated to working position, the block *g*², into which screws the pin that forms the bearing for the roller, 40 presses against the upper edge of the scale plate pressing it rearwardly as will be seen in Fig. 2. The scale plate being of spring metal or being resilient serves as a retaining spring that bears upon the flat face of the 45 block *g*² to hold the roller in operative position. The scale plate and arms *g*, *h*, are preferably all resilient. The block *g*² has a projection *g*³ from its front edge and when the roller is thrown forward as in Fig. 3, the 50 projection comes against the arm *g* and supports the roller in horizontal position. Both roller clamps are mounted in their respective arms in the same way.

Referring to Fig. 4, it will be seen that it 55 shows substantially the same arrangement. The type bar guide and ribbon vibrator are, however, omitted. The card holders in this figure are shown as sheet metal trowel-like parts *k* extending across the line of print, 60 their small or pointed ends being uppermost. They are concavo-convex as seen in Fig. 5, the convex side, curved in the direction of the length of the platen, being contiguous to and out of contact with the platen and 65 being also curved in the direction of the

circumference of the platen. These holders may, as seen in Fig. 5, be hinged to the upper ends of the arms or standards *g*, *h*, in the same manner as are the rollers shown in Figs. 2 and 3. For some reasons, however, 70 I prefer that, of whatever form they may be, they shall swing laterally. A convenient way in which this may be effected is shown in Figs. 4, 6 and 7 which illustrate the trowel shaped paper holders. The outer edges of the arms or standards *h*, *g* at their upper portions have enlarged or lateral extensions *g*^x, *h*^x. These extensions are disposed in a plane oblique to the axis of the platen and have formed in their front faces two circular depressions *m*, *o*. These depressions are in a line oblique to the scale and a prolongation of which would extend obliquely across the front face of the platen intersecting the circumferential line in which the printing point is located. The holders are formed with obliquely disposed extensions *k'* which are pivoted intermediate the two circular depressions to the standard *h*, *g*, by pivots or screw bolts *k*². The two circular depressions *m*, *o* are the same distance from the axis of the pivot and in the end of the extensions *k'*, at the same distance from the axis of the pivot *k*² as the 80 depressions *m*, *o*; there is a depression 85 made in the metal forming a concavo-convex protuberance in the under side thereof. Since both the parts *k'* and their supporting standards are more or less elastic, the 90 holders may be swung laterally and will be held frictionally either in elevated position, as indicated at the right hand side of Fig. 4, or in depressed condition, as indicated at the left hand side of that figure and in Fig. 7. 95

Fig. 8 shows a paper holder of the general character disclosed in Fig. 4 except that it has at the bottom a straight spindle *r* that seats in apertures in two forwardly projecting flanges *r*¹, *r*² at and adjacent the upper end of the supporting standard *g* or *h*. In this form of the device the paper holders may be lifted bodily from engagement with their supporting arms and so removed from 100 in front of the line of print.

In Fig. 9, the standard *h* has immovably 115 connected with it a roller paper holder whereas the standard *g* shows a roller with a spindle *s*, that is removably seated in forwardly projecting flanges *s*¹, *s*² on the standard *g*.

In Fig. 10, paper holders of still another construction are removably carried by each of the arms *g*, *h*. Each of these holders is made as follows: The upper part *t* is cylindrical and at a point above the upper edges of the scale *i* it is tapered inwardly as at *t*². The lower end of the tapered part has secured to it a rather heavy coiled spring *t*². The lower end of the spring is connected to a spindle *t*³ and the spindle is removably 125 130

5 seated in lips or flanges *u*, *u'* projecting from the front face of the standard. A paper holder of this kind is in itself yielding or elastic and when mounted as shown and described may be removed bodily from in front of the printing line.

10 In all forms of paper holders that have been described, the surface thereof, coöperating with the platen, flares or is curved outwardly at each side so that the edge of a card or sheet will readily be directed between the holder and the platen.

15 The paper holders or fingers are so shaped as to conform more or less circumferentially to the platen and since when in operative position they lie closely adjacent, or against, the surface of the platen they should, if moved laterally from in front of the line of print, swing in a plane oblique to the axis 20 of the platen in order to properly clear the same. This is clearly shown in Figs. 4, 6 and 7.

I claim:

25 1. In a front strike writing machine, the combination with a platen of an upright support disposed in front of the platen, stationary relative to the movement of the platen and terminating adjacent the printing line and a paper holder hinged thereon 30 and adapted to swing upwardly across the printing line into operative relation to the platen.

35 2. In a front strike writing machine, the combination with a shifting platen of an upright support disposed in front of the platen, stationary relative to the movement of the platen and terminating adjacent the printing line and a paper holder hinged thereon 40 and adapted to swing upwardly across the printing line into operative relation to the platen when the platen is in either of its positions.

45 3. In a visible writing machine, the combination of a platen, a paper guide extending from below upwardly in front of the platen, stationary relative to the movement of the platen and terminating below the printing line and a paper holder pivoted upon said guide and adapted to be swung 50 into upright position in which it extends across the line of print and into lowered position in which it is removed from in front of the line of print.

55 4. In a visible writing machine, the combination with a shiftable platen and the carriage shift rail of paper guiding and holding devices comprising a support permanently mounted on the shift rail and terminating at or below the line of print and a paper holder mounted upon said support and adapted to be swung upwardly and laterally to extend across the line of print and downwardly and laterally to remove it from the line of print.

60 5. In a visible writing machine, the com-

bination with a shiftable platen and the shift rail of the machine, of a paper guide permanently mounted on the shift rail extending up in front of the platen and terminating at or below the line of print and 70 a paper holder coöperating with the platen and mounted upon such guide so as to be swung to either of two positions, a lower one in which it is removed from the line of print and an upper one in which it extends across the line of print. 75

6. In a visible writing machine, the combination with a shiftable platen and the shift rail of the machine, of a support and paper guide stationary relative to the movement 80 of the platen and mounted on the shift rail, extending up in front of the platen and terminating at or below the line of print, a paper holder coöperating with the platen and mounted upon such support 85 so as to be adjusted to either of two positions, a lower one in which it is removed from the line of print and an upper one in which it extends across the line of print and a platen line scale bar carried by or forming part of said support. 90

7. In a visible writing machine the combination of a platen, a support normally extending from below up in front of the platen to a point below the line of print and 95 a paper holder with a rear face curved in the direction of the length of the platen and endwise in the direction of its circumference coöperating with the surface of the platen, movably mounted upon said support 100 in a position in which it extends above the line of print and adapted to be moved relatively to said support from in front of the line of print. 105

8. In a visible writing machine, the combination of a platen, a flexible support and paper guide comprising a platen line scale and extending from below up in front of the platen to a point at or below the line of print and a paper holder mounted upon 110 said guide and adapted to be raised to extend across the line of print and to be lowered from in front of the line of print.

9. In a visible writing machine an upright arm stationary with respect to the transverse travel of the platen, extending up in front of the platen and terminating at or below the printing line combined with a paper holder pivoted thereon to turn laterally of the machine adapted to extend across 115 the printing line and to be swung laterally from in front of the printing line. 120

10. In a visible writing machine, a platen, a coöperating paper holder curved in the direction of the circumference of the platen 125 and a support, stationary relative to the transverse travel of the platen, upon which said holder is pivoted to swing laterally in the plane oblique to the axis of the platen said holder being adapted to extend across 130

the line of print and coöperate with the platen or to be swung downwardly from in front of the line of print.

11. In a visible writing machine, a shifting platen, a support shifting with the platen, extending up in front thereof and stationary with respect to the transverse movement thereof and a paper holder mounted to swing on said support whereby it may be arranged to extend across the line of print and coöperate with the platen or be moved from in front of the line of print.

12. In a visible writing machine, a platen, a coöoperating paper holder curved in the direction of the circumference of the platen and extending across the printing line thereon and a support upon which the holder is mounted to move forwardly in a direction

away from the plane in which the printing surface of the platen lies.

13. In a front strike writing machine, a platen, a coöperating paper holder curved in the direction of the circumference of the platen and extending across the printing line thereon and a support extending up in front of the platen upon which the holder is mounted to swing forwardly and downwardly away from the vertical plane in which the printing line on the platen lies.

In testimony whereof, I have hereunto subscribed my name.

EDWARD B. HESS.
